Inventor

James H. Roden
by H. S. Dennison
Atty.

UNITED STATES PATENT OFFICE.

JAMES H. RODEN, OF TORONTO, ONTARIO, CANADA.

ELECTRIC GASLIGHTER.

Application filed December 1, 1922. Serial No. 604,268.

To all whom it may concern:

Be it known that I, JAMES H. RODEN, a subject of the King of Great Britain, and resident of the city of Toronto, county of York, Province of Ontario, in the Dominion of Canada, have invented certain new and useful Improvements in Electric Gaslighters, described in the following specification and illustrated in the accompanying drawings, that form part of the same.

The principal objects of the invention are to eliminate the dangers and inconvenience in the use of matches in the lighting of gas burners and fires of various kinds, and to devise a very simple, safe and inexpensive device which will be very easily operated.

The principal features of the invention consist in the novel construction and arrangement of parts whereby a step down transformer and a pressure switch is enclosed within a small casing which may be conveniently handled and to which is attached a tube projection carrying an electrically heated lighting element within a perforated guard, the whole structure being adapted for connection to the ordinary lighting A. C. circuit.

In the drawings, Figure 1 is a top plan view of the igniter device.

Figure 2 is a longitudinal sectional view of my device.

Figure 3 is a cross sectional view through the line 3—3 of Figure 2.

It has been previously proposed to utilize an electrically heated element for igniting gases and other combustibles and to transform an alternating current to a low voltage high amperage flow and I do not claim broadly this idea. I have however produced a very simple and compact device which is herein illustrated as a shell type transformer having the primary winding 1 and secondary winding 2 mounted on the core 3. This transformer is enclosed within a symmetrical casing 4 which may be easily held in the hand and within one end of which is arranged the push button switch 5.

The lead 8 from the flexible cord 7 is connected to the primary winding 1 and the other lead 6 from the cord 7 is connected with the contact member 14 of the switch 5. The other contact member 13 of the switch 5

is connected with the lead 9 from the other end of the primary winding.

The switch 5 is formed of an insulating block 10 secured to the inner wall of the casing 4 by rivets or screws 11. A groove 12 in the upper side of the block 10 houses the stationary and spring contact members 14 and 13 which are firmly secured by the rivets 16 and 15 respectively.

A push button 17 is arranged in a recess 18 midway of the length of the groove 12 and projects through an opening in the casing 4 and is readily pressed by the thumb or finger of the hand holding the casing. Downward pressure on the button presses the spring contact 13 against the contact 14 and the circuit through the primary winding is established.

One terminal 19 of the secondary winding 2 is secured to the casing 4 and the other terminal 20 extends into a metal tube 21 projecting from one end of the casing 2. This tube is provided at its outer end with a perforated cap 22 and an insulating block 23 fitted in the outer end of the tube carries a copper stud 23' which is secured to the terminal 20 and at its outer end is connected to a nichrome wire coil 24. The outer end of the coil 24 is secured to the cap and the secondary circuit is established through the tube 21. The high ampere low voltage current heats the coil 24 to incandescence and it readily lights any combustible gas or vapour.

The construction of the device is extremely compact and may be utilized where an A. C. circuit is available.

The device is a complete transformer unit requiring no interference with wiring and no installation of apparatus of a permanent nature and it may be moved about at will.

What I claim as my invention is:—

1. An electric gas lighter, comprising, a transformer having its primary connected with a current circuit, a switch in said primary circuit, a casing enclosing said transformer and switch, a member projecting from said casing, and a heating element supported from said projecting member and connected with the secondary winding of said transformer.

2. An electric gas lighter, comprising, a

small symmetrical casing to be held in the hand, a push button switch secured in said casing at one end, a step down transformer arranged within said casing and having flexible leads from the primary winding, 5 said switch being included in said primary winding, a metal tube secured in one end of said casing and having a perforated metal

cap at its outer end, a nichrome wire coil arranged in said perforated cap and connected with one lead of the secondary coil of said transformer the secondary circuit being closed through the metal tube and casing and cap. 10

JAMES H. RODEN.
